ATTORNEY

UNITED STATES PATENT OFFICE.

BENJAMIN H. MAHAFFEY, OF EUGENE, OREGON.

MOP.

1,188,294.

Specification of Letters Patent. Patented June 20, 1916.

Application filed January 14, 1916. Serial No. 72,143.

To all whom it may concern:

Be it known that I, BENJAMIN H. MAHAFFEY, a citizen of the United States, residing at Eugene, in the county of Lane and State 5 of Oregon, have invented certain new and useful Improvements in Mops, of which the following is a specification.

This invention relates to mops and has for its principal object to provide means for 10 wringing a mop without removing the same from the floor.

Another object of the invention is to provide a receptacle in receiving communication from the wringing means to receive the 15 dirty water as it is swung from the mop.

With the foregoing and other objects in view, the invention consists in the novel features of construction, combination and arrangements of parts as will be hereinafter 20 more fully described, illustrated in the accompanying drawings, and claimed.

In the drawings: Figure 1 is a top plan view of a mop constructed in accordance with the invention, parts thereto being 25 shown in sections. Fig. 2 is a side elevation, the handle being broken away. Fig. 3 is a vertical longitudinal section through the container and rollers.

Referring to the drawings by numerals 30 wherein is illustrated the preferred embodiment of my invention, 1 designates a substantially rectangularly shaped container having end walls 2, and upwardly and inwardly converging front and rear walls 3, 35 the container being opened at the top as is illustrated in the drawings.

The brackets 4, are secured to the end walls of the container 2, and are provided at their upper ends with openings to receive 40 the ends of a shaft 5, carrying a roller 6. The upper ends of the brackets 4, project but slightly above the upper edge of the container, so that the roller will be positioned between the end walls of the container 45 and will extend slightly thereinto as is clearly illustrated in Fig. 3 of the drawings.

One end of the shaft 5, extends outwardly past the brackets and has journaled thereon 50 a beveled gear 7, which meshes with a similar gear 8, upon one end of a shaft 9. This shaft 9, is carried within a sleeve 10', which is provided at its lower end with a housing 10 inclosing the gears 7 and 8, the said hous-

ing being journaled loosely upon a collar 55 formed on the gear 7, so that the same may be swung vertically as will be understood. The sleeve 10, forms one arm of the operating handle for the mop and is provided at its upper end with a second housing 11, 60 which has secured thereto a rod 12, forming the upper end of this side of the operating handle. A bevel gear 13 is secured upon the outer end of the shaft 9, and meshes with a similar gear 14, carried by a transversely 65 extending shaft 15. The housing 11, incloses the gears 13 and 14 and has bearings therein to receive the shaft 15, carrying an operating crank 16, to be operated for wringing the mop. The end of the shaft 5, opposite 70 to that carrying the gear 7, extends outwardly past the brackets 4, and has journaled thereon for vertical swinging movement, the lower end of a bar 17, the said bar forming the second side of the operating handle and being connected with the rod 12, by a hand grip bar 18. If desired the shaft 15, may be extended through one face of the housing 11 and journaled in a suitable bearing provided upon the bar 17, 80 75 to provide a rigid handle structure.

Each of the brackets 4, is provided with a laterally extending projection 19 at its lower end and each of these laterally extending projections has pivoted thereto, as at 20, 85 the lower end of one of the links 21. These links are arranged in parallelism with the brackets 4, and have openings formed in their upper ends in alinement with the bearing openings in the brackets 4. A second 90 roller 22 is journaled in the openings in the upper ends of these links and is arranged with respect to the container in a manner similar to the roller 6. Contractile coil springs 23, connect the links 21, with the 95 brackets 4, and exert a tension to swing the upper ends of the links toward the brackets, to move the rollers into engagement. A plurality of bands 24, of any desired material, are arranged over the angular side 100 faces of the container and about its end face and pass over the roller 6, and under the roller 22, as is clearly illustrated in Fig. 3 of the drawings. Any desired number of these bands may be provided and the same 105 are held in spaced relation by means of a transversely extending bar 25, secured in the end walls of the container and having down-

wardly extending spaced projections 26, arranged between the bands to hold the same against lateral movement, relative to the container. The bands 24, form the cleaning or mopping portions of the device, which is operable manually through the medium of the handle 18.

- After the floor has been cleaned, and it is desired to mop the same by means of the 10 improved device, the container is passed over the floor to permit of the bands absorbing the water thereon. The handle 16, is then rotated, which will, through the medium of the gears 14, 18, shaft 9 and gears 15 8 and 7, turn the roller 6. The bands 24, being firmly engaged over the roller 6, will thus be slid about the converging front and rear walls of the container, to bring the portion thereon, originally in engagement with 20 the under face of the container, between the rollers 6 and 22. The tension of the springs 23, drawing the roller 22 against the roller 6, will act as a wringer, as the handle 16, is rotated to press the water from the bands. 25 A portion of the water will be forced directly through the bands and will fall into the container, while the rest of the water will flow through the spaces between the bands and also into the container. After the 30 container has become filled with water, the same may be carried to any convenient position and emptied.

From the foregoing description taken in connection with the accompanying drawings, it is thought that the construction and operation of the improved mop will be clearly understood and while I have herein shown and described one specific embodiment of my invention, I do not wish to be limited thereto, except for such limitations as the claims may impart.

What is claimed is:

1. A device of the character described comprising a container, a band arranged about said container, rollers carried by said container, said band being arranged between said rollers, a handle for moving the container and means on the handle for rotating one of said rollers.
2. A device of the character described comprising a container, bands arranged about said container, rollers carried by said container, said bands being passed between said rollers, a handle mounted for vertical swinging movements relative to said container and means carried by said handle for rotating one of said rollers.
3. A device of the character described comprising a container, a plurality of bands carried by said container, means for wringing said bands and a rod having a plurality of projections thereon for engagement between the bands to hold the same in spaced relation.
4. A mop comprising a container, bands

arranged about said container, brackets carried by said container, a roller journaled in said brackets, said bands being passed over said roller, links pivoted to said brackets, a roller carried by said links, said bands being passed under said second roller, spring means to swing the links toward the first roller, means to move the container, and means to rotate one of said rollers.

5. A mop comprising a container, rollers carried by said container, mopping means associated with said rollers, a gear carried by one of said rollers, a housing inclosing said gear, said housing being mounted upon said gear for swinging movement, a shaft, a gear upon said shaft in engagement with said first-mentioned gear, a sleeve carried by said housing, a second housing formed upon the opposite end of said sleeve, said shaft being passed through said sleeve and having a gear thereon arranged within the second housing, a shaft supported by said second housing, a gear on said last-mentioned shaft, in mesh with said last mentioned gear, and a crank to rotate said last mentioned gear, said housings, and said sleeve forming a portion of the operating handle of the mop.

6. A device of the class described comprising a container, a band arranged about said container, brackets mounted upon the opposite ends of said container, a roller carried by said brackets, said brackets having turned lower ends, links pivoted to said turned lower ends, a second roller mounted in said links, means for rotating the first-mentioned roller, said band being engaged around said first-mentioned roller, and means for resiliently retaining the second-mentioned roller in binding engagement with said band.

7. A mop comprising a container having inclined side portions, a plurality of bands engaged around said container, the top of said container being open, a roller supported across the open top of said container, said bands being engaged around said roller, means for pressing said bands against said roller, means for rotating said roller, and means for retaining said bands in spaced relation.

8. A mop comprising a container having inclined forward and rear portions and an opening having a plurality of bands engaged around said container, brackets projecting upwardly from the ends of said container, a roller mounted in said brackets, said bands being engaged around said roller, a handle for said mop, said handle including rotating means for said roller, means for pressing said bands against said roller, and a separating means for said bands.

9. A mop comprising a container, bands engaged around said container, brackets mounted upon the ends of said container, a roller mounted in said brackets, a handle

mounted upon said roller, said bands being engaged over said roller, means for tightening said bands upon said roller, tension means for the last-mentioned means, and means for spacing said bands upon said container.

In testimony whereof I affix my signature in presence of two witnesses.

BENJAMIN H. MAHAFFEY.
